CLAIM

The ornamental design for a sheet material with hexagonal perforations, as shown and described.

DESCRIPTION

FIG. 1 is a top perspective view of the sheet material with hexagonal perforations.

FIG. 2 is a front detail view of the sheet material with hexagonal perforations.

FIG. 3 is a right side detail view of the sheet material with hexagonal perforations; and,

FIG. 4 is a bottom view of the sheet material with hexagonal perforations.

(Continued)

The present design is a flexible sheet material with hexagonal perforations as shown.
